His attorney

UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

CAR ROOF.

Application filed April 15, 1922. Serial No. 553,113.

To all whom it may concern:

Be it known that I, CHARLES DAVID BONSALL, a citizen of the United States, a resident of the city of Pittsburgh, county of Allegheny, and State of Pennsylvania, have invented a certain new and useful Improvement in Car Roofs, of which the following is a specification.

This invention relates principally to metal car roofs of the all-steel riveted-up type wherein the roofing sheets extends from side plate to side plate and are riveted thereto and have their side margins raised, lapped and riveted together to form hollow weather-proofing seams or joints that function as roof supporting carlines.

The principal object of the present invention is to produce a roof that will be stiffer and stronger than previous roofings of the same weight of metal; and the invention consists principally in the shape and arrangement of the lapped stiffening ribs which function as carlines. The invention also consists in the parts and arrangements of parts hereinafter described and claimed.

In the accompanying drawing, which forms part of this specification and wherein like symbols refer to like parts wherever they occur,

Fig. 1 is a plan view of a portion of a car roof embodying my invention, parts being shown broken away to disclose portions located beneath the roofing;

Fig. 2 is an enlarged transverse section through one half of the roof in the line 2-2 in Fig. 1;

Fig. 3 is a longitudinal section along the ridge line of the roof on the line 3-3 in Fig. 1;

Fig. 4 is a similar section between the ridge and the eaves on the line 4-4 in Fig. 1;

Fig. 5 is a similar section through the roof adjacent the eaves on the line 5-5 in Fig. 1; and

Fig. 6 is an enlarged vertical cross-section through the eaves portion of a car showing a seam whose eaves end construction is slightly modified.

The present roof comprises heavy gage roof sheets 7 arranged cross-wise of the car and supported on and rigidly secured by rivets 8 to the uppermost flanges of angle bar side plates 9. The eaves ends of the roof sheets are provided with depend-

ing flanges 10 which overhang the outer margins of the side plates. The roof sheets, which are preferably pressed from sheet blanks of uniform width, slope upwardly from the eaves to the ridge and have their side marginal portions formed into raised stiffening ribs A of gradually decreased depth and gradually increased width from the ridge to the eaves.

Each of the ribs A comprises a nearly vertical web portion 11 that forms the inner side of the rib and has at the top thereof a flat portion 12 that extends outwardly or laterally with relation to the body of the sheet and forms the top of the rib, both of these portions extending from end to end of the sheet. The web portions of the ribs of each sheet converge slightly from ridge towards each end of the sheet and gradually diminish in height from ridge towards each end of said sheet. At the ridge, each rib is of inverted channel section with a horizontal marginal flange; that is, the horizontal portion 12, which forms the top of the rib, has a down-turned portion 13, which forms the outer wall of the rib and has a flange 14 projecting outwardly from the bottom thereof in the plane of the body of the sheet. As the depth of the web 11 of each rib decreases from ridge to eaves, there is corresponding increase in the width of the top portion 12 of said rib from the ridge to the eaves; and there is also a corresponding decrease in the width of the horizontal marginal flange 14 from the ridge to points substantially midway of the ridge and eaves where it merges into the plane of the outer wall 13 of the rib at the lower edge thereof. From this point there is a gradual decrease in the depth of the outer wall 13 of each rib to points adjacent to the eaves where it merges into the plane of the top portion 12 of the rib at the outer margin thereof. From these points, the ends of the ribs are turned downwardly and merge into the plane of the body of the sheets, where the sheets are turned down to form the depending drip flanges 10.

The reversely tapered inner side walls 11 and top walls 12 of the ribs permits the use of a sheet blank having parallel sides, thereby eliminating the expense of shearing the blank to a special shape before pressing; and the surplus metal resulting from the down-turned eaves ends of the ribs is

preferably turned down to form depending outer side walls 15, which increase in depth from the points where the outer portions 13 of the ribs merge into top portions 12 there-
⁵ of to points directly over the side plates where said portions are turned outwardly in the plane of the sheets to form lateral marginal flanges 16. Thus, the ribs have ridge portions of inverted channel section,
¹⁰ which gradually change to L-shape sections at points adjacent to the eaves, and have eaves portions of inverted channel section which are curved downwardly and merge into the plane of the sheets at the ends
¹⁵ thereof.

The sheets are assembled by lapping the rib of one sheet over the rib of an adjacent sheet, and the top portions of said ribs are rigidly secured together by rivets 17, there-
²⁰ by forming a roof having rigid weather proofing seams that function as carlines. The lateral marginal flanges 16 that appear in the downwardly curved sections of the lapped ribs are secured to the adjacent body
²⁵ portions of the sheets by means of the rivets 8 that secure the eaves ends of the roof sheets to the side plates.

Running boards 18 extend longitudinally of the roof at the ridge and are securely
³⁰ bolted to the upwardly offset horizontal flanges of metal running board saddles 19, which are arranged crosswise of the roof. The lower flanges of the running board saddles rest on the top of the seams and are se-
³⁵ cured thereto by means of the rivets 17 that secure the lapped ribs together.

The lapped ribs form seams of gradually decreased depth and gradually increased width from ridge to eaves; and said lapped
⁴⁰ ribs, by reason of their cross-sectional shape, form inverted channel shaped seams having side walls of double thickness at the ridge which gradually change into a single thickness near the eaves where they again
⁴⁵ change into a double thickness. This ar-
⁵⁰ rangement results in a seam construction which gradually changes from a high and narrow double-walled section at the ridge, adapted to withstand the vertical roof load, to a low and wide single-walled inverted channel section near the eaves, adapted to withstand the horizontal stresses; and the
⁵⁵ downwardly curved channel shaped ends of the seams are further strengthened to withstand horizontal stresses by rigidly securing the marginal base flanges 16 at each side of the seam and the adjacent body portions of the sheets to the side plates.

The modified seam construction shown in
⁶⁰ Fig. 6 is similar to that shown in Figs. 1 to 5, the only difference being that the downwardly and outwardly flanged portions 13 and 14 formed by the surplus metal resulting from the downwardly curved eaves ends
⁶⁵ of the ribs are omitted, whereby the eaves

sections of the ribs or seam flanges A are of inverted L-shape section and cooperate to form seams whose eaves sections comprise tops of double thickness and sides of single thickness. This arrangement is brought
⁷⁰ about by removing the four corners of the sheet blank..

The hereinbefore described construction admits of considerable modification without departing from the invention. Therefore, I
⁷⁵ do not wish to be limited to the exact de-
⁸⁰ tails shown and described.

What I claim is:

1. A car roof comprising a plurality of roof sheets whose side margins are connected together to form hollow seams having side walls of double thickness at the ridge and of single thickness adjacent to the eaves.
⁸⁵

2. A car roof comprising a plurality of roof sheets whose side margins are connected together to form hollow seams of greater depth at the ridge than at the eaves, said seams having side walls of double thickness at the ridge and of single thickness adjacent
⁹⁰ to the eaves.

3. A car roof comprising a plurality of roof sheets whose side margins are connected together to form hollow seams of greater width at the eaves than at the ridge, said seams having side walls of double thickness at the ridge and of single thickness adjacent to the eaves.
⁹⁵

4. A car roof comprising a plurality of metal roof sheets whose side margins are lapped and rigidly secured together to form hollow seams that function as carlines, said seams being of increased width and decreased depth from ridge to eaves where they merge into the plane of the sheets, said seams having side walls which gradually change from a double thickness of metal at the ridge to a single thickness of metal adjacent to the eaves.
¹⁰⁵

5. A car roof comprising a plurality of metal roof sheets whose side margins are lapped and rigidly secured together to form hollow seams that function as carlines, said seams being of increased width and decreased depth from ridge to eaves where they merge into the plane of the sheets, said seams having side walls which gradually change from a double thickness of metal at the ridge to a single thickness of metal adjacent to the eaves and thence again
¹¹⁰ change into a double thickness of metal at the eaves.
¹¹⁵

6. A car roof comprising a plurality of roof sheets having raised ribs at their side margins which are lapped to form hollow seams, said ribs having marginal base flanges which are widest at the ridge and gradually decrease in width towards the eaves.
¹²⁵

7. A car roof comprising a plurality of
¹³⁰

- 6 roof sheets having raised hollow ribs at their side margins that are lapped to form hollow seams, said ribs having marginal base flanges at the eaves and at the ridge 6 that merge into the side walls of said ribs at points intermediate the ridge and eaves. 8. A car roof comprising a plurality of roof sheets having raised hollow ribs at their side margins that are lapped to form 10 hollow seams, the outer side wall of a rib being deepest at the ridge and gradually decreasing in depth on opposite sides of the ridge from the bottom of said rib towards the top thereof. 15. A car roof comprising a plurality of roof sheets having raised hollow ribs at their side margins that are lapped to form hollow seams, the outer side wall of a rib being deepest at the ridge and gradually decreasing in depth to points adjacent to the eaves where it merges into the top of the 20 rib. 10. A car roof comprising a plurality of roof sheets having raised hollow ribs at their side margins that are lapped to form hollow 25 seams, the outer side wall of a rib being deepest at the ridge and gradually decreasing in depth towards the eaves and having a lateral base flange that is widest at the 30 ridge and gradually decreases in width towards the eaves. 11. A car roof comprising a plurality of roof sheets having raised hollow ribs at their side margins that increase in width 35 and decrease in depth from ridge to eaves where they merge into the plane of the sheets, said ribs being lapped to form hollow 40 seams, the outer wall of a rib having a minimum depth at points intermediate the ridge and eaves and gradually increasing in depth from said points to the plane of the sheet where it terminates in the form of horizontal ridge and eaves flanges. 12. A car roof comprising a plurality of 45 roof sheets having raised hollow ribs at their side margins that increase in width and decrease in depth from ridge to eaves where they merge into the plane of the sheets, said ribs being lapped to form 50 hollow seams, the outer wall of a rib having a minimum depth at points intermediate the ridge and eaves and gradually increasing in depth from said points to the plane of the sheet where it terminates in the form of horizontal ridge and eaves flanges whose width decreases from the ridge towards the eaves and from the eaves towards the ridge, respectively. 13. A car roof sheet having its side 55 margins formed into hollow ribs, said ribs having marginal base flanges that are widest at the ridge and gradually decrease in width towards the eaves. 14. A car roof sheet having its side marginal portions formed into hollow ribs, the outer walls of said ribs being deepest at the ridge and gradually decreasing in depth on opposite sides of the ridge from the bottoms of the ribs towards the tops thereof. 15. A car roof sheet having its side marginal portions formed into hollow ribs, the outer wall of a rib being of a minimum depth at the points intermediate the ridge and eaves and gradually increasing in depth from said points to the plane of the sheet where said outer wall is turned outwardly to form marginal ridge and eaves flanges. 16. A car roof sheet having its side marginal portions formed into hollow ribs, the outer walls of said ribs being of a minimum depth at the points intermediate the ridge and eaves and gradually increasing in depth from said points to the plane of the sheet where they are turned outwardly to form marginal ridge and eaves flanges. 17. A car roof sheet having its side marginal portions formed into hollow ribs, said ribs being of substantially channel shaped section at the ridge and gradually changing to ribs of substantially L-shaped section adjacent to the eaves where they merge into the plane of the sheets. 18. A car roof sheet having its side marginal portions formed into hollow ribs of substantially L-shaped section at points intermediate the ridge and eaves and gradually changing to substantially channel shaped sections at the ridge and eaves. 19. A car roof sheet having its side marginal portions formed into hollow ribs of substantially L-shaped section at points intermediate the ridge and eaves and gradually changing to substantially channel shaped sections at the ridge and eaves, the outer walls of said channel shaped sections being turned outwardly in the plane of the sheet to form marginal flanges. 20. A car roof sheet having its side marginal portions formed into hollow ribs of substantially L-shaped section at points intermediate the ridge and eaves and gradually changing to substantially channel shaped sections at the ridge and eaves, the outer walls of said channel shaped sections being turned outwardly in the plane of the sheet to form marginal flanges, the marginal flanges of the channel shaped ridge portions of said ribs being widest at the ridge and gradually decreasing in width on opposite sides thereof and the marginal flanges of the channel shaped eaves portions of said ribs being widest at the eaves and gradually decreasing in width towards the ridge. Signed at St. Louis, Mo., this 13th day of April, 1922.

CHARLES DAVID BONSALL.
